UNITED STATES PATENT OFFICE.

HENRY L. FERRIS, OF HARVARD, ILLINOIS.

DOOR-HANGER.

SPECIFICATION forming part of Letters Patent No. 498,467, dated May 30, 1893.

Application filed August 20, 1892. Serial No. 443,556. (No model.)

To all whom it may concern:

Be it known that I, HENRY L. FERRIS, a citizen of the United States of America, residing at Harvard, in the county of McHenry and

5 State of Illinois, have invented certain new and useful Improvements in Barn-Door Hangers, of which the following is a specification.

My invention relates to improvements in barn-door hangers, its object being to provide a hanger in which the members attached to the door are so adjustable with reference to the parts supported by the track that the position of the door with reference to the vertical plane of the track may be readily changed 15 as desired.

The invention is fully described and explained in this specification and shown in the accompanying drawings; in which—

Figure 1 is a rear elevation of a carrier embodying my invention, the carrier being shown in operative relation to a door and track. Fig. 2 is a transverse vertical section through the line 2—2, Fig. 1, the view being in the direction indicated by the arrow in 25 said figure. Fig. 3 is a transverse vertical section through the line 3—3, Fig. 1, the view being in the same direction as in Fig. 2. Fig. 4 is a vertical section between and parallel to the bars A, A, of the carrier; and Fig. 5 is an 30 end elevation of a modified form of carrier.

In the first four figures, A, A are two parallel bars held together at their ends by clamping plates B, B', lying above and below the bars, the proper space between the 35 bars being maintained by a flange b, formed on either one of the clamping plates and lying between the bars. Beneath the lower face of each of the plates B', lies a horizontal extension C', formed on the upper end of a 40 vertical bar C, which extends downward and is adapted to be fastened to the outer face of a door. Each of the extensions C', lies at right angles to the bars A, A, and is formed with a longitudinal slot S, Fig. 3, through which 45 passes a bolt extending upward through the clamping plates B, B', and provided with a nut by means of which the extension C', the clamping plates B, B', and the ends of the bars A, A, may be firmly fastened together. 50 The slots S, S, in the two extensions C', C',

provide for the adjustment of the bars C, C, with reference to the vertical planes of the bars A, A, for the purpose hereinafter set forth.

Each of the bars C, C, is provided with a 55 stop D, permanently fastened to it at a suitable distance below the bars A, A, and this stop serves as a gage for fastening the bars C, C, to the door, it being only necessary to place the hanger in such a position that the 60 stops D, D, shall rest against the upper edge of the door in the manner indicated in Figs. 1 and 2. These stops are a great advantage in the attachment of the hanger to the door as it is essential that the bars A, A, be parallel to the edge of the door, and that the 65 two hangers which are fastened to the upper edge of each door be in the same line, and without the stops it is a matter of some difficulty to fasten the hangers in exactly the 70 right position.

Each of the bars A, A, is provided with the usual dependent stirrup F, and the ends of the arbor g, of a roller G, lie in the spaces between the stirrups and the corresponding 75 bars in a manner well known in this class of devices. The roller G, of each hanger rests upon a rail H, which may be of any desired form corresponding to the form of the roller and may be supported in any desired manner. 80

Fig. 5 illustrates a construction in which the two bars A, A, of the hanger are connected by means of an arched bar B², which takes the place of the clamps B, B', and spacing lip b, of the device shown in the other 85 figures. The bar B, has at its lower end a horizontal extension B³, beneath which lies the horizontal extension C', of the bar C fastened to the door. The extension C', is slotted as in the other figures and the bars C, C, of the hanger may be adjusted with reference to the planes of the bars A, A, in the manner already described. In the device having the construction shown in this figure, a stop D, may, if desired, be fastened, to each of the 90 bars C, C, but I prefer to make the downwardly extending portion of the bar B², of such length that the upper edge of the door 95 may coincide with the upper face of the extension C', the joint between the parts B³, C', 100

being thus used as a gage for the attachment of the bars C, C, to the door. 35

In the form shown in the first four figures it is possible to dispense with the clamping plate B', the upper face of the extension C', of each of the bars C, being then brought into contact with the lower edges of the bars A, A. I prefer, however, to use the clamping plates below the edges of the bars A, A, since these plates may be formed with upturned lips at their ends which prevent spreading apart of the ends of the bars A, A. 40

It is evident that the adjustment of the bars C, C with reference to the vertical planes of the bars A, A, or with reference to the plane of the roller must correspondingly adjust the door with reference to the vertical plane of the track when all the parts are in working relation. The object of this adjustment is to compensate for irregularities in the door, or the wall along which it slides, whether these irregularities be caused by warping or in other ways. As a rule, at the time that doors are hung they are new and are practically plane, but it often happens that after a period of use they are so warped as to rub and grind against the parts beside which they move in opening and closing. In all such cases the adjustability which forms an important feature of my invention permits adjustment of the doors with very slight trouble. 45

Having now described and explained my in-

vention, what I claim as new, and desire to secure by Letters Patent, is—

1. In a door hanger the combination with a roller-frame comprising two parallel bars and a roller lying between said bars and supported thereby, of transverse clamping plates lying above and across said parallel bars, members adapted to be fastened to a door and provided at their upper ends with extensions lying beneath and across said bars and bolts passing through said extensions and said clamping plates and between said bars; substantially as shown and described. 45

2. The combination with the parallel bars, A, A, clamping plates, B, B', and members, C, C, formed with slotted horizontal extensions, C', C', of bolts passing through said extensions and clamping plates and between said bars and adjustably securing the members, C, C, to said bars; substantially as shown and described. 50

3. In a door hanger frame, the combination with parallel bars A, A, of clamping plates B, B', lying above and below the edges of the bars, one of said plates being provided with a flange b, lying between the bars and maintaining the proper space between them; substantially as shown and described. 55
